FOLDABLE AND ADJUSTABLE SAWHORSE

Filed May 16, 1929

UNITED STATES PATENT OFFICE

LUTHER V. CLINE, OF SAN DIEGO, CALIFORNIA

FOLDABLE AND ADJUSTABLE SAWHORSE

Application filed May 16, 1929. Serial No. 363,446.

My invention relates to saw horses, more particularly to foldable and adjustable saw horses, and the objects of my invention are: first, to provide a saw horse in which the legs thereof fold together and against the back of the saw horse, thereby forming a compact bundle suitable for easy transportation; second, to provide a saw horse which is rigid and sturdy of construction when 10 in its open position; third, to provide a saw horse in which the wood portions thereof protect the tools of a user from contact with the metal portions of the saw horse; fourth, to provide a saw horse the height of which 15 may be readily varied; fifth, to provide a saw horse which is adjustable so as to rest solidly although the surface upon which it rests is uneven; sixth, to provide a means in connection with a saw horse of this class 20 which positively holds the legs thereof in various shifted positions, but which may be readily released when desired; seventh, to provide a novel hinge mechanism especially adapted for a saw horse of this class, and 25 eighth, to provide a saw horse which is extremely simple of construction proportional to its functions, durable, efficient in its action and which will not readily deteriorate or get out of order.

With these and other objects in view as 30 will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Fig. 1 is a fragmentary side elevational view of my saw horse; Fig. 2 is a fragmentary end elevational view thereof; Fig. 3 is an enlarged fragmentary sectional view thereof through 3—3, of Fig. 2; Fig. 4 is an enlarged 40 fragmentary sectional view thereof through 4—4 of Fig. 3; Fig. 5 is an enlarged fragmentary end elevational view, from the line 5—5 of Fig. 1; Fig. 6 is a plan view of the brace locking means with parts and portions broken away and in section to facilitate the

illustration; Fig. 7 is a substantially diagrammatical view of the sawhorse in its folded position.

Similar characters of reference refer to similar parts and portions throughout the 55 several views of the drawings.

Back member 1, shielding plate 2, leg members 3, hinge leaves 4, hinge body 5, leg hinge leaves 6, brackets 7, pin members 8, brace members 9, washers 10, springs 11, securing 60 means 12 and catches 13, constitute the principal parts and portions of my saw horse.

The back member 1 is formed of a piece of wood having a substantially rectangular cross-section and suitable length. Its upper 65 surface is protected by a shielding plate 2, also of wood, which is secured thereto by screws 2a. These screws are countersunk as far as possible into the shielding plate, so that the tools of the carpenter will not come 70 in contact therewith.

Four leg members 3 are provided, one pair near each end of the back member 1. Hinge leaves 4 are secured to the underside of back member 1 near each end thereof. A hinge body 5 is secured to each hinge leaf at the side of said hinge leaf facing the corresponding end of the back member. A leg hinge leaf 6 is adapted to be pivotally secured to the hinge body 5 along each side thereof, as 75 shown best in Figs. 3 and 4. The hinge leaves 6 pivot about an axis which is at right angles to the pivotal axis of the hinge body 5. Each hinge leaf 6 is secured to the upper inner side 80 of one of the leg members 3. It is preferred to have the plane common to each pair of legs 3 intersect the back member 1 at an angle a few degrees off the perpendicular therewith, so that the extended ends of the pair of 85 legs are further apart from each other than their secured ends, thereby bracing the back member 1 against end movement. The extended end of each hinge body 5 which terminates substantially flush with the outer 90 side of its corresponding leg members, is provided with a depending integral bracket 7. Each bracket is provided with a slot 7a extending longitudinally therewith adapted to receive a pin member 8.

Pivottally secured in superposed relation on the pin member 8 against the rear side of the bracket 7 are the one ends of a pair of braces. Each brace member 9 extends downwardly and outwardly and is pivotally secured by means of a screw 9a or the like to the outer side of one of the leg members as shown best in Fig. 2. The pin 8 extends inwardly from the brace members 9 between the corresponding pair of legs 3 and terminates in a head portion 8a, as shown best in Fig. 3. Between the head 8a and the inner brace 9 are two washers 10 which are resiliently held apart by a spring 11. The other end of the pin 8 extends into the slot 7a and is screwably mounted in a securing means 12.

The securing means 12 is provided with two lugs 12a on its face which rides against the outer side of the bracket 7. These lugs 12a are adapted to engage any oppositely disposed pair of a plurality of holes 7b formed in the bracket 7 along opposite sides of the slot 7a, as shown best in Fig. 5. The securing means 12 is also provided with a ring 12b adapted to be engaged by a finger. The spring 11 tends to hold the lugs 12a in interlocking relation with the holes 7b. An outward pull on the ring 12b disengages the lugs 12a from the holes 7b and permits the shifting of the securing means longitudinally with the bracket, thereby bringing the legs 3 nearer together or moving them further apart, depending upon which direction the securing means is shifted.

A cut-out portion 1a is provided in each end at the under side of the back member 1. Each cut-out portion 1a is adapted to receive a catch member 13. The catch member is confined within the cut-out portion 1a except for a catch portion 13a thereof which is adapted to project through a slot 5a formed near the extended end of the hinge body and engage the one margin. The catch portion 13a is adapted to firmly hold the hinge body against the under side of the back member 1. A handle portion 13b of the catch member 13 extends towards the corresponding end of the back member 1 past the margin of the corresponding bracket member 7, where it may be readily engaged by pressing upwardly into the outer end of the cut-out portion 1a. The handle portion is normally held downwardly by means of a spring shown by dotted lines in Fig. 3 of the drawings. Although the catch is housed by the back member 1, so that the saw or other tools of the user will not come in contact with it, it is readily accessible.

The saw horse is folded by shifting the securing means 12 towards the back 1, thereby bringing the extended ends of the corresponding pair of legs against each other, then releasing the catches 13 and pivoting the hinge bodies with the legs 3 about the axes of said hinge bodies with the hinge leaves 4.

This brings the legs to the position as shown in the diagrammatical view Fig. 7. The members of one pair of legs are brought against each other, while the members of the other pair of legs are brought against the outside of the first pair. The positions of the holes 7b and the brackets 7 may be so arranged that when the legs are in the position shown in Fig. 7, the lugs of each securing member register with the holes 7b so as to lock the legs in this position and enable the saw horse to be transported without danger of the legs shifting to an extended position.

As indicated in Figs. 1 and 2, and by the dotted line in Fig. 7, the pair of legs which, when folded, constitute the outer pair, may be provided with pegs. These pegs fit into corresponding sockets on the outer sides of the other pair of legs, thereby enabling the securing means 12 to hold the leg members 3 in fixed folded position.

Although I have shown and described a particular construction, combination and arrangement of parts and portions, I do not wish to be limited to this particular construction, combination and arrangement of parts and portions, but desire to include in the scope of my invention the construction, combination and arrangement substantially as set forth in the appended claims.

Having thus described my invention, what I claim as new and desire to secure by Letters Patent is:

1. In a saw horse, a back member, leg members, a pair of base members, hinge means for connecting pairs of said legs to each of said base members, other hinge means for connecting said base members to said back members, catch means for holding said base members against said back members so that said pairs of legs extend outwardly therefrom, bracket means depending from each of said base members, brace means secured to the members of each pair of legs and pivotally connected with said bracket means, and a securing means for holding said brace members in any one of several positions relative to said bracket means.

2. In a saw horse, a back member, leg members, hinge means for connecting pairs of said legs to a common base member, other hinge means for connecting said base members to said back members, said leg members adapted by reason of said hinge means and said base members to fold against said back member, with the legs of one pair embracing the legs of the other pair and substantially parallel therewith and interlocking means on contiguous opposite ended legs for securing said leg members in such folded position.

3. In a saw horse, a back member provided with a recess in its lower side, leg members, a base member hinged in a transverse axis to

the lower surface of one end portion of said back member, means for securing a pair of legs to said base member, a catch member operably positioned in said recess in the lower side of said back member, a portion of said base member normally overlapping said recess, said catch member adapted to engage said overlapping base portion for holding said legs in extended relation relative to said

10 back member.

4. In a saw horse, a back member, a base member comprising a portion rigidly secured to the lower surface of one end portion of said back member, a pivoted portion hinged to 15 said rigid portion in a transverse axis relative to said back member, a pair of leg members hinged to the side portions of said pivoted portion at right angles to said transverse axis, said pivoted portion having a right 20 angularly bent bracket portion extending substantially intermediate said legs, a catch member adjustably mounted on said bracket portion, and brace members extending from said catch member to said legs for permitting 25 angular adjustment thereof relative to said bracket member, said hinged base member allowing said legs to be folded against the lower surface of said back.

5. The construction as set forth in claim 4 30 including a catch member operably mounted on said back member adjacent said pivoted base portion and engageable therewith when said legs are in their extended position relative to said back member.

35 6. In a saw horse, a back member, a pair of mutually adjustable legs provided with socket means therein, common means hinging said legs at their upper ends to one end portion of said back member and permitting 40 said legs to be folded inwardly against the lower surface of said back member, a second pair of legs supported in like manner at the opposite end of said back member and foldable against the lower surface thereof and 45 with the inner sides of said legs substantially contiguous with the outer surfaces of said first pair of legs, said contiguous legs lying substantially parallel and a pin in one leg of each pair adapted to enter said socket means 50 in the contiguously lying leg of the other pair for preventing movement of said pairs of legs away from the lower surface of the back member.

55 In testimony whereof I have hereunto set my hand at San Diego, California, this 9th day of May 1929.

LUTHER V. CLINE.
